TAPERED END STRAND MASS

John H. Garrott, Bloomfield, N. J., assignor to
The Clark Thread Company, Newark, N. J., a
corporation of New Jersey

Application February 10, 1942, Serial No. 430,223

5 Claims. (Cl. 242—161)

This invention relates to the structure of a strand mass wound and carried on a bobbin.

In the art of marketing and using strand masses carried on a mandrel, spool or bobbin, it has been found desirable to control the structure of the mass so that it will have a tapered end opposite the base of the bobbin, as this has been found to facilitate the delivery of the filament, as for example thread, cord and the like, therefrom and for this purpose the strand mass is conventionally wound on a spool, bobbin or mandrel having a cylindrical arbor portion and a tapered base. In the conventional thread winding machines the thread is presented to the rotatably mounted bobbin by means of a thread guide which is reciprocated axially in relation to the axis of the bobbin through a path of fixed amplitude and the thread wound on the bobbin by what is termed a cross wind. By employing mechanism which advances the bobbin axially during the winding thereof a tapered wind is obtained, that is, the end of the strand mass opposite the base of the bobbin has a configuration such that when the mass is viewed in a direction perpendicular to the axis of the bobbin the end thereof opposite the base has a straight taper and appears to be substantially a truncated cone structure.

When such spools or bobbins are placed in use, as for example on sewing machines, it has been found that there is a tendency for the filament to uncoil too freely at the base of the bobbin with the result that snarls and other difficulties are likely to occur. Moreover, another difficulty arises in the use of the spools having the straight taper mentioned. In the treatment of thread, as for example the dyeing of colored thread and the like, lack of uniformity of shade is likely to occur and in the spools or bobbins having straight taper at the end this lack of uniformity shows up as a mass or series of splotches due, apparently, to the reflection of light from the smooth and regular surface of the tapered end.

It is an object of the present invention to remove these difficulties and to provide an improved strand mass.

The principles of the invention will be defined in the appended claims and will be most clearly understood by the description of certain specific illustrative embodiments thereof taken in conjunction with the accompanying drawings, in which:

Fig. 1 is an elevation of one form of the improved strand mass carried on a mandrel or bobbin;

Fig. 2 is a similar view partly in section;

Fig. 3 is a plan view of the same looking down on the tapered end;

Fig. 4 is a view of a different form;

Fig. 5 is a view of a third form.

Referring first to Figs. 1, 2, and 3, there is shown a spool having a cylindrical or hollow arbor portion 1 and a tapered base 2. On the spool there is initially wound an annular layer 3 which has a predetermined radial thickness and a predetermined length, this layer 3 being preferably adjacent to the external surface of the arbor 1. Ordinarily the several radially successive strand layers are wound from the same continuous length of strand, e. g. thread, cord and the like. The next succeeding axially offset layer 4 is wound upon the layer 3. Layer 4 may have the same radial thickness as 3 and will have substantially the same axial length. At the end of the spool opposite the tapered base 2 the layer 4 is axially offset to a predetermined degree in relation to the preceding layer 3 and, as shown, this offset is in a direction parallel to the axis of the bobbin and toward the base 2 thereof. At the end of the layer 4 adjacent said base 2 that portion of layer 4 which is immediately adjacent said base is radially offset to a predetermined degree in relation to the remainder of layer 4 in a direction toward the axis of the spool. Each radially successive annular layer, offset axially and radially as described, is then built up in like manner.

This structure is most clearly shown in Figure 2. At the base 2 of the bobbin the surface of each successive radially offset layer of the strand mass is substantially perpendicular to the axis of the bobbin and forms an acute angle with the surface of the tapered base 2.

The apparatus or mechanism for producing the structure illustrated is not a part of the present invention. It is, however, preferred to employ the apparatus described in my copending application Serial No. 416,193, filed October 23, 1941, now U. S. Patent 2,301,693, November 10, 1942. By means of this mechanism the bobbin may be automatically, intermittently and controllably advanced axially of the mandrel upon which it is revolvably mounted while the thread is fed to said bobbin through a thread guide carried on a transverse bracket reciprocating axially of the bobbin through a path of constant and predetermined magnitude, to produce the stepped or offset wind shown.

The successive axially offset strata 3 to 8, for example, may have the same or different radial

thicknesses and the degree to which they are offset axially of the bobbin in relation to each other may also be varied, with the result that instead of a series of steps of uniform dimensions these dimensions may be varied to any predetermined degree. The structure preferred is, however, that shown in Figs. 1 and 2.

The building up of each of the layers 1 to 8 is continued until the desired radial thickness is obtained, the axial length of each of said layers being determined by the fixed amplitude of the traverse mechanism of the conventional winding machine. When the said layer is completed the bobbin is then thrust forward to a predetermined degree by suitable mechanism (as for example that described in my above identified copending application). Since the path of the thread guide is fixed and constant by virtue of the traverse mechanism, the next succeeding layer is axially offset in relation to the preceding layer at the end of the bobbin opposite the base to an extent determined by the forward axial thrust of the bobbin. When the thread of the strand mass of each next succeeding layer reaches the end of its traverse adjacent the base of the bobbin that thread falls into the space between said end of the preceding layer and the tapered base of the bobbin and, owing to this effect, the end of the said next succeeding layer immediately adjacent the base of the bobbin becomes radially offset in relation to the remainder of the mass of that layer. This will be clear from an inspection of Fig. 2.

By the mechanism referred to, the thread is wound spirally on the mandrel by a cross wind. In unwinding it follows the same path as that followed in winding, but in the reverse direction. Each core of thread adjacent the base of the bobbin is located at the apex, e. g. the apex 9, of the angle subtended between the tapered base 2 and the adjacent strand mass surface perpendicular to the axis of the bobbin. In the conventional strand mass structure, the coil adjacent the base expands due to the natural resilience thereof, but in the described structure this expansion is restrained, the surface of the strand mass perpendicular to the axis of the bobbin forming with the adjacent surface of the bobbin, a recess which prevents undue expansion. The coil is, so to speak, releasably locked in this recess, although the retaining or locking effect does not interfere with the satisfactory delivery of the strand or thread.

The axial offset of the successive layers at the end of the bobbin opposite the base thereof provides a configuration such that when the strand package of Figs. 1 to 3 is viewed in a direction perpendicular to the axis of the bobbin the generally tapered end presents the appearance of a series of ascending and descending right-angle steps, as shown in Figs. 1 and 2. One of the advantages of this structure is that light rays falling thereon are reflected in such a manner that lack of uniformity in dyeing and other treatments does not appear and the salability of the article is thereby improved.

Referring to Figs. 4 and 5 inclusive, these show, as already stated, modified configurations of the tapered end of the bobbin opposite the base

thereof. By means of suitable mechanism which is not a part of the present invention, preferably that set forth in my said copending application, the configuration of the tapered end may be widely varied, and by reference to said copending application it will be noted that said configuration corresponds to the configuration of the cam which controls the axial advancement of the bobbin.

Fig. 4 shows a tapered end the configuration of which is essentially a series of ascending and descending scallops concave toward the axis of the bobbin. Fig. 5 is substantially the negative of Fig. 4, the ascending and descending scallops being convex toward the axis of the bobbin.

15 I claim:

1. An article of manufacture comprising a mass of yarn or the like wound on a bobbin, said bobbin having an arbor portion and a tapered base; said mass having a stepped end formation at the end 20 of the bobbin and receding toward the base, said formation comprising a plurality of layers of yarn of substantially equal length, each of substantial radial thickness, and the starting point of each 25 layer following the first being substantially spaced lengthwise of the bobbin from the starting point of the preceding layer, the first layer terminating, adjacent the tapered end of the bobbin, in a surface substantially perpendicular to the axis of the arbor, which surface forms with the surface of the tapered base an annular recess; the second 30 layer extending into and occupying said recess and itself forming with the adjacent surface of the tapered base an annular recess; and so on with each successive layer.

35 2. An article of manufacture comprising a mass of yarn or the like wound on a bobbin, said bobbin having an arbor portion and a tapered base; said mass having a stepped end formation at the end 40 of the bobbin and receding toward the base, said formation comprising a plurality of layers of yarn of substantially equal length, each of substantial radial thickness, and the starting point of each 45 layer following the first being substantially spaced lengthwise of the bobbin from the starting point of the preceding layer a distance commensurate with the lengthwise offset of the ends of the layers remote from their starting points, incident to the taper of the base.

3. An article of manufacture comprising a mass 50 of yarn or the like wound on a bobbin, said mass composed of a plurality of layers of equal length, each of a substantial radial thickness and each starting at a point axially removed a substantial distance from the starting point of its preceding 55 layer, thereby providing an end structure of stepped form receding from one end of the bobbin, and said layers together providing a uniform outside diameter throughout the length of the mass from the last step to the base of the bobbin.

60 4. An article of manufacture as defined in claim 3 in which the end of the bobbin remote from such stepped end formation is tapered and engages each layer, following the first, throughout the thickness thereof.

65 5. An article of manufacture as defined in claim 3 in which the exposed end of each layer presents a curved surface extending from the inner to the outer edge of each such layer.

JOHN H. GARROTT.
